John R. Mitchell.

UNITED STATES PATENT OFFICE.

THOMAS B. RICE, OF PHILADELPHIA, PENNSYLVANIA.

PACKAGE.

1,274,198.

Specification of Letters Patent. Patented July 30, 1918.

Application filed March 23, 1918. Serial No. 224,098.

To all whom it may concern:

Be it known that I, THOMAS B. RICE, a citizen of the United States, residing at Philadelphia, in the county of Philadelphia and State of Pennsylvania, have invented certain new and useful Improvements in Packages, of which the following is a specification.

The principal object of the present invention is to provide an efficient and comparatively inexpensive package for cylindrical objects having flat bases and more or less pointed ends, which shall be constructed of inexpensive and easily produced elements capable of being kept in stock and of re-use.

Other objects of the invention will appear from the following description, and the invention will be claimed at the end hereof, but will be first described in connection with the embodiment of it chosen for illustration in the accompanying drawings forming part hereof and in which—

Figure 1, is a transverse sectional view of a package embodying features of the invention.

Fig. 2, is a sectional view drawn to a reduced scale and taken at right-angles to the section of Fig. 1.

Fig. 3, is a perspective view illustrating details of construction, and

Fig. 4, is a sectional view illustrating a modification.

In the drawings 1, is a six sided or generally rectangular box of which one side 2, is detachable and may be regarded as the cover. There are strips of which some 3, are substantially rectangular with two hollow edges 4 extending the full length thereof, and of which others 5, are sections (shown as half sections) of the first with one hollow edge 4^a extending the full length thereof. 6, are grooves ranging crosswise of the strips 3 and 5, and in them are arranged crosspieces 7, which may have a hollow face 8.

For the sake of a further description of the invention *a*, are cylindrical objects having flat bases *b*, and more or less pointed ends *c*. The objects *a*, are shown as bottles but bottles are selected merely for the sake of description as there are many similarly shaped objects to the packing and transportation of which the package of the invention

is applicable. The strips 3, can be quickly and cheaply made from available sizes of lumber and the strips 5, can be obtained by dividing the strips 3, or by making them by the same machinery. These strips 3 and 5, thus cheaply made by ordinary wood working machinery, can be carried in stock or stored before or after cutting them to length 60 to fit between opposed walls, usually end walls, of the box 1. The cross-pieces 7, may be obtained and treated in a similar manner and there is no difficulty in making the transverse grooves 6, in the strips. The parts that 65 make up the package can be rapidly and cheaply produced by existing machinery and without the employment of skilled labor.

In assembling the package strips 3 and 5, extending between opposed walls, usually 70 the end walls, of the box are laid on the bottom of the box and the cross-pieces 7, are arranged in the transverse grooves 6. Then articles *a*, are placed so as to be supported by the hollow edges 4 and 4^a, of the strips 75 and the face of the cross-pieces 7. A double row of strips is then placed on top of the articles, as shown in the drawings, and more articles are arranged upon them, and finally another row of strips is placed on top of the 80 second row of the articles. When the cover 2, is applied to the box, the strips, while detached from the box and easily removable for unpacking the articles, wedge the articles between four sides of the box and so safely 85 pack them. The articles are packed endwise by the cross-pieces 7, and as shown by having their bases in abutment with the end walls of the box. Eight articles are shown as packed in a box but the number is not important. The hollow edges of the strips may be grooved, for example as shown at 9, Fig. 4, if it is desirable to reduce the surface of contact between the articles and the strips, and the shape of the faces 8, may be changed 90 to conform to the shape of the articles to be 95 packed.

What I claim is:

1. A carrier comprising the combination of a rectangular box, transversely grooved 100 strips detached from the box and extending lengthwise between two of its opposed walls and of which some are rectangular with two hollow edges and of which others are

sections of the first with one hollow edge, and cross-pieces arranged in said grooves, substantially as described.

2. In a carrier the combination of parallel strips of which some are rectangular with two hollow edges extending throughout the length thereof and of which others are sections of the first with one hollow edge ex-

tending throughout the length thereof, and cross-pieces having hollow faces, there being ¹⁰ grooved relation between the cross-pieces and strips to permit the hollow edges and hollow faces to coöperate, substantially as described.

THOMAS B. RICE.
